US00D480371S

(12) **United States Design Patent** (10) Patent No.: **US D480,371 S**
Sako et al. (45) Date of Patent: ** Oct. 7, 2003

(54) **SEMICONDUCTOR DEVICE**

(75) Inventors: **Shigeki Sako**, Yokohama (JP);
Masahiro Ootomo, Kitakyushu (JP);
Kazuyoshi Fukuda, Kitakyushu (JP);
Takahiro Ide, Yokohama (JP)

(73) Assignee: **Kabushiki Kaisha Toshiba**, Tokyo (JP)

(**) Term: **14 Years**

(21) Appl. No.: **29/161,321**

(22) Filed: **May 29, 2002**

(30) **Foreign Application Priority Data**

Nov. 30, 2001 (JP) 2001-035198

(51) LOC (7) Cl. **13-03**

(52) U.S. Cl. **D13/182**

(57) **CLAIM**

The ornamental design for a semiconductor device, as shown and described.

DESCRIPTION

FIG. 1 is a front, bottom and right side perspective view of a semiconductor device, showing our new design;

FIG. 2 is a front elevational view thereof;

FIG. 3 is top plan view thereof; a bottom plan view being a mirror image thereof;

FIG. 4 is a right side elevational view thereof; a left side elevational view being a mirror image thereof; and,

FIG. 5 is a rear elevational view thereof.
